FUEL SUPPLY SYSTEM

Byron B. Stroud, New York, N. Y., assignor to
 Atlantic States Gas Company, Inc., New York,
 N. Y., a corporation of Delaware

Application May 2, 1936, Serial No. 77,601

14 Claims. (Cl. 220—85)

This invention relates to fuel supply systems and more particularly to one for furnishing an inflammable gas for domestic consumption.

In isolated communities in which the ordinary urban inflammable gas service is not available, the benefits of such service are absent and potential consumers lack the acknowledged advantages of the use of gas in domestic appliances. Even in regions served by a public gas system the expense involved is sometimes found to be prohibitive. The purpose of the present invention is to make it possible for individual homes to each have its own source of gas and to make this available at low cost.

With this purpose in view, it is an object of the invention to provide means for the supply of gas which is safe from explosion and danger of asphyxiation.

Another object is to provide means in such a system for insuring a constant supply at a uniform pressure.

Another object is to facilitate the determination of the consumption of fuel and the need for replenishment.

The particular manner in which these objects and other objects of the invention are obtained will be apparent from the following description.

In the drawings—

Figure 1 is an elevation showing the general layout of a preferred embodiment of the system.

Fig. 2 is a detail sectional view of part of Fig. 1.

Fig. 3 is a detail in elevation of the controls at the tank.

Fig. 4 is a plan of Fig. 3.

Fig. 5 is a vertical sectional view of a gauge.

The stove 10 and water heater 11 are representative of the domestic appliances which may be supplied with fuel by the system of this invention. Gas is supplied to them through the usual pipes 12 leading from the metering device 13. The especial features of this metering device as here applied will hereinafter be set forth.

The metering device 13 receives fuel through a low pressure regulating valve 14. This valve 14 is supplied with fuel through a conduit 15 connected to a high pressure regulating valve 16 at the underground tank 17. A tube 18 extending to the bottom of the tank 17 supplies valve 16 with fuel through a regulable excess flow valve 19.

Tank 17 is placed underground at a distance from the house in order that danger of harm resulting from an explosion will be minimized. This places the tank out of the way and where it will not be subject to rapid changes in tempera-

ture. Since it is away from the house, any leakage from the tank is likely to escape to the atmosphere before reaching the house.

Projecting upwardly from the tank is a riser or dome 21 carrying various controls and presenting them closer to the ground level. As here shown, these controls include a filling valve 22 through which the tank is replenished, and a gauge 23 for determining the level of the liquid in the tank, as well as the valves 16 and 19 mentioned. If desired, a safety valve 23x may be provided.

To keep the ground away from the dome 21 and permit access thereto, a curb box 24 is superimposed between the tank and the ground level. Since the tank 17 will ordinarily be of rounded cross section, rest pieces, as saddles 25, may be mounted directly on the tank. These saddles present a flat upper surface upon which the curb box 24 rests. It will be noted that due to the 15 saddles, and due also to the curved surface of the tank, a space exists at 26 by which any gas escaping into the ground can find its way into the curb box and thence to the atmosphere.

To convey any gas escaping from the portion 20 of tube 15 between the tank and the house, into the curb box for dissipation to the atmosphere, this portion of the tube is enclosed by a casing 27. The end of this casing at the house is sealed into the wall 28 thereof, and is also sealed to the conduit 15. The other end of the casing 27 opens into the interior of the curb box. Any gas within the casing obviously cannot pass into the house, but can only escape into the curb box.

While any suitable cover may be provided for 35 the curb box, as here shown, the cover 29 is fully locked against removal. For this purpose the cover 29 carries a depending arm 30 which enters a recess in the interior wall of the curb box. Opposite from this arm 30 the cover is 40 locked in place by the usual bolt and lock arrangement shown at 31.

The fuel used is forced into the tank 17 under such pressure that it exists in the tank in the liquid state, although under normal conditions 45 it exists as a gas. Such a fuel is generally known and forms no part of this invention. It may be noted that as an example a mixture of propane and butane may be used. Such a mixture will exist as a liquid at seventy pounds per sq. in. 50 pressure at seventy degrees Fahrenheit.

The high pressure regulating valve 16 preferably should reduce the pressure of the fuel to from three to five pounds pressure per sq. in. in the conduit 15. The low pressure regulating 55

valve 14 reduces the fuel to the final pressure at which it is to be used in the appliances. Ordinarily this will be a few ounces per sq. in. By reducing the pressure in these successive steps, an improved regulation is had. Not only is it assured that there will be but slight pressure variation at the burner during use, but it is possible to prevent the pressure from rising in pipe 12 at the time no fuel is being consumed.

10 Ordinarily the liquid in tank 17 will pass into its gaseous state immediately after passing through valve 16. However, if sufficient heat is not at once absorbed into the fuel, so that liquid flows through conduit 15, the fins, or webs, 33, before valve 14 will bring sufficient heat to the fuel to complete the transformation into a gas. Since the liquid fuel in changing into a gas must absorb a considerable amount of heat because of the latent heat of vaporization, any moisture 20 either in the fuel, or upon the exterior of the pressure regulating valves, will freeze. Such solidification of moisture upon the interior and exterior of the regulating valves interferes seriously with their operation.

25 The moisture within the fuel itself, although existent in a nearly imperceptible amount, will, upon freezing in the valve passageway, interfere with the proper closing and opening of the valve. To prevent such freezing of this moisture, it is a 30 feature of this invention to add to the liquid fuel in tank 17 a substance having a low freezing point, and one with which the moisture is soluble. Such a substance has been found to be anhydrous ethyl alcohol. The moisture and the ethyl alcohol dissolved therein will not freeze, but will 35 remain as a liquid in passing through the valve. For this purpose, it has been found to be only necessary that the ethyl alcohol be present to the extent of $\frac{1}{10}$ of 1% by volume.

40 With regard to the trouble arising from the freezing of moisture on the exterior parts of the pressure regulating valves, this is principally due to ice forming upon the diaphragm 34 thereof. This would obviously prevent free action of the diaphragm. To prevent this interference with 45 the operation of the diaphragm, it has been found that by filling the portion of the valve casing on the side of the diaphragm opposite from that which is subjected to the delivered fuel, with a liquid having a low freezing point, that all difficulties are eliminated. For this purpose a U-tube 50 34a may be connected to the casing to allow for the rise and fall of the liquid. It has been found that glycerine gives excellent results.

55 To ascertain the level of the liquid in the tank, the gauge 23 is used. This consists of a tube 36 passing through a packed opening of the tank, and having a valve 37 at its outer end. By opening this valve 37 and withdrawing the tube until gas appears, the liquid level is determined.

60 Since the fuel used in this system has an extremely high heat value, it may be desirable to calibrate the meter on the basis of the heat units consumed. This may be done by referring the 65 gas consumption to the standard heat value for local gas furnished by a utility. Thus, the meter will indicate the quantity of local gas which has been required to deliver the same amount of heat. Instead of the meter registering the actual cubical consumption of gas, it will therefore register some multiple of this equal to the quotient of the 70 heat value of local gas, and the heat value of the fuel used in the system.

Inasmuch as a given quantity of liquid fuel 75 will expand into a definite volume of gas at the

final pressure and temperature conditions at which it is consumed, it can be determined from the amount of gas recorded by the meter as being actually consumed, how much liquid has been withdrawn from the underground tank. In carrying out this practice, an index may be used to which the gas consumed as recorded by the meter may be referred to indicate the corresponding quantity of liquid used. Thus, the need for replenishment may be ascertained directly from the meter itself, and the possibility of unexpected exhaustion will be removed.

What is claimed is:

1. In combination in a fuel supply system, a tank for retaining a gas under a sufficient pressure to maintain its existence in a liquid state, conduit means opening into the tank below the level of the liquid therein for withdrawing the fuel and conveying it to a point of use, a pressure reducing means in said conduit and adjacent the tank for reducing the pressure of the fuel to an intermediate pressure, and a reducing valve adjacent the point of use and in said conduit for reducing the pressure to a final pressure suitable for use. 25

2. The combination in a system for supplying fuel to a building, of an underground tank located apart from the building, an underground conduit leading from the tank to the building to convey fuel thereto for consumption, a casing 30 inclosing the portion of said conduit between the building and the tank, said casing being sealed to the conduit at the building, but being open at the end near the tank, whereby fuel escaping into the space between the casing and conduit can pass 35 to the atmosphere only at the tank.

3. The combination in a system for supplying fuel to a building, of an underground tank located apart from the building, a curb box extending from the tank upwardly to the ground level 40 to provide access to the tank, an underground conduit leading from the tank to the building to convey fuel thereto for consumption, a casing inclosing the portion of said conduit between the building and the tank, said casing being sealed 45 to the conduit and to the wall of the building through which it passes to prevent escape into the building of gas in the space between the conduit and casing, said casing at its other end passing through the curb box and being unsealed to 50 the conduit whereby gas in the space between the conduit and casing can only escape into said curb box and to the atmosphere.

4. A fuel supply system comprising an underground tank, a curb box surmounting said tank 55 and extending upwardly to the ground level, rest means between the tank and the curb box for supporting the lower edge of the curb box above the tank to provide a passageway for escape of gas into said curb box and to the atmosphere. 60

5. A fuel supply system comprising an underground tank having a curved upper surface, saddle members resting on said curved surface of the tank, and a curb box supported on said saddle members and extending upwardly to the ground 65 level, said saddle members spacing the curb box above the tank to provide a passageway for the escape of gas through the curb box to the atmosphere.

6. A fuel supply system comprising an underground tank having a convexly curved upper surface, a dome projecting upwardly from said tank toward the ground level, a curb box surrounding said dome and extending between the tank and the ground level, and rest means on 70

the tank on opposite sides of said dome presenting substantially flat upper surfaces for receiving said curb box.

7. In combination in a fuel supply system, an underground tank for storage of the fuel, a curb box supported by said tank and extending between said tank and the ground level to permit access to the tank, and a cover plate for closing the top of said curb box, said cover plate having depending means at one side for engaging with said curb box, and locking means at the opposite side of said cover for preventing elevation of said cover and disengagement of said depending means.

15 8. In combination in a fuel supply system, a tank for storing the fuel under pressure, a conduit leading from said tank to a point of consumption of the fuel, and a supply limiting valve in said conduit between the tank and the point 20 of fuel consumption, said valve being regulable whereby it will remain open during normal flow of fuel and will close upon an abnormal flow of fuel in the same direction.

9. In combination in a fuel supply system, a tank for the storage of the fuel under a sufficiently high pressure to maintain its existence in a liquid state, a conduit connecting said tank to a point of consumption of the fuel, a pressure reducing valve in said conduit and a metering 30 device in said conduit on the low pressure side of the reducing valve, said device being calibrated to read in units equivalent to the thermal value of standard fuel.

10. In combination in a fuel supply system, a tank for the storage of the fuel under a sufficiently high pressure to maintain its existence in a liquid state, a conduit connecting said tank to a point of consumption of the fuel, a pressure reducing valve in said conduit and a metering 40 device in said conduit on the low pressure side of the reducing valve, and an index associated with said metering device for indicating the quantity of fuel remaining in said tank.

11. In apparatus of the class described, a tank 45 to hold fuel in liquid form, a conduit extending from a point below the liquid level of said tank to convey the liquefied gas from the tank, a high pressure reducing valve in said conduit adjacent the tank, a low pressure reducing valve in said 50 conduit between the high pressure reducing valve and the point of consumption, and means provided on said conduit in advance of said low

pressure reducing means for absorbing heat to insure a gaseous state of said fuel as it reaches the low pressure reducing valve.

12. In apparatus to supply gas to a building, a tank for holding liquefied gas, a curb box 5 mounting said tank, a conduit extending from a point in said tank below the liquid level up into the curb box, and adapted to extend thence below ground into the building, a high pressure reducing valve in said conduit located within the curb 10 box, a low pressure reducing valve in the building, and on said conduit, and a casing for collecting escaping gas from said conduit, said casing opening into the curb box, substantially as described.

15 13. In combination in a fuel supply system, a tank for retaining a gas under a sufficient pressure to maintain its existence in a liquid state, conduit means opening into the tank below the liquid surface for withdrawing the fuel and conveying it to a point of use, and pressure reducing means in said conduit for reducing the pressure of the liquid therein to a pressure at which it will exist in a gaseous state, said tank being buried in the ground, and said conduit leading underground 20 from the tank to the house which is to be supplied with gas, the first step pressure reduction taking place in that portion of the conduit lying outside the house, and the second step pressure reduction taking place at a point in said conduit within 25 the house, substantially as described.

14. In combination in a fuel supply system, a tank for retaining a gas under a sufficient pressure to maintain its existence in a liquid state, conduit means opening into the tank below the liquid surface for withdrawing the fuel and conveying it to a point of use, and pressure reducing means in said conduit for reducing the pressure of the liquid therein to a pressure at which it will exist in a gaseous state, said tank being buried 30 in the ground, and said conduit leading underground from the tank to the house which is to be supplied with gas, the first step pressure reduction taking place in that portion of the conduit lying outside the house, and the second step pressure reduction taking place at a point in said conduit within 35 the house, substantially as described.
